UNITED STATES PATENT OFFICE.

ARNOLD F. GLASS, OF BIRMINGHAM, ALABAMA.

OIL-BURNING STOVE.

1,276,901.

Specification of Letters Patent. Patented Aug. 27, 1918.

Application filed April 2, 1918. Serial No. 226,185.

To all whom it may concern:

Be it known that I, ARNOLD F. GLASS, a citizen of the United States of America, residing at Birmingham, in the county of Jefferson and State of Alabama, have invented certain new and useful Improvements in Oil-Burning Stoves, of which the following is a specification.

This invention relates to improvements in oil burning stoves and ranges.

One feature of my invention relates to stoves in which the products of combustion are controlled by dampers so as to pass either around or through the oven to the stack and constitutes an improvement on the oil burning stove forming the subject matter of Letters Patent No. 1,258,210, issued to me on the 5th day of March, 1918. In my said patent if the slide valve controlled bottom ports in the oven which admit the products of combustion thereinto were left closed when the damper was set to direct the products of combustion through the oven to the stack instead of directly to the stack, it is obvious that the connection to the stack would be shut off by the closure of the oven bottom ports with the result that the burners would be smothered and put out. To overcome this difficulty I provide a safety draft port in the bottom of the oven which is controlled by a damper that is moved by the main draft controlling damper mechanism so that it will be open when such main damper mechanism is set to pass the hot gases through the oven. This safety draft port is sufficiently large to prevent the smothering of the burners and yet not large enough to interfere with the proper regulation of the supply of heat that is admitted into the oven under the control of its bottom slide valves.

I have found that it is essential in oil burner stoves to control the volume of air to the stove, and a further feature of my invention is to design a simple means to this end by the provision of a horizontal baffle plate which is provided with flanged openings through which the burners pass, the circular flanges serving as centering supports for the bases of the burner stacks or chimneys. The partition thus prevents access of air into the stove except such as is drawn in normal course through the burner stacks and this is regulated as to volume by suitable slide valves.

My invention will be better understood by reference to the accompanying drawings in

which I illustrate the preferred embodiments thereof, but it will be understood that the details of construction may be widely varied without departure from the essential principles of my invention.

According to the drawings:—

Figure 1 is a plan view of the stove with the top broken away to show the division plate which supports the burner chimneys in plan.

Fig. 2 is a vertical sectional view showing the top and bottom ports opening from the top of the oven and from below the oven into the common outlet flue.

Fig. 3 is a partial vertical sectional view taken on the line 3—3 of Fig. 2.

Fig. 4 is an enlarged detail view showing the main slide damper and its connection to the draft relief port valve.

Fig. 5 is a view similar to Fig. 3 of a modified damper and safety draft valve construction.

Fig. 6 is a detail view of the slide valve controlling the bottom and side ports of the oven.

Similar reference numerals refer to similar parts throughout the drawings.

My present invention may be embodied in any standard type of cooking stove, the stove illustrated in the drawings comprising a bottom 1, end walls 2 and 3, a front wall 4 and a back wall 5. The top 6 is formed by an ordinary stove casting with removable stove lids 7. The stove is provided with an ordinary hinged front door 8 and a hinged downwardly swinging end door 9 in the end wall 2 through which access is had to the valves 10 for the burners 11 in the fire box 12 of the stove. These burners are adapted to burn kerosene or any suitable fuel oil which is contained in a tank 14 and supplied to the burners by means of a pipe 15 in the manner well understood in this art. The tops of the burner chimneys 16 are disposed slightly below the top wall 17 of the oven, which has its end adjacent to the burners extended downwardly to engage the bottom 1 of the stove and laterally to engage the front and rear walls 2 and 4, thus forming a partition which forces the products of combustion to pass from the fire box 12 and enter a top flue or passage way 19 above the oven along which they flow under the top 6 of the stove to the right hand end of the oven and thence downwardly between the oven and the end wall 3 of the

stove and back under the oven to an outlet port 20 which opens into the bottom of the stove flue 21. The bottom wall 22 of the oven is provided with several series of bottom ports 23 adapted to be opened and closed by a sliding ported valve 24 which slides in guides 25 attached to the under face of the bottom 22. The outer end of the slide valve is bent to form a handle 26 which projects through the front wall 4 of the stove. A similar arrangement of ports, valves and guides may be provided for the top of the right end wall of the oven. Near the top of the oven I provide an outlet port 27 having access to the stove flue 21. The bottom oven wall 22 is also provided with a safety draft port 28 adjacent to the port 20 and this port 28 is adapted to be closed by a valve 29 hinged to the bottom wall 22 at 30 and having a rigid operating arm 31 which, when the valve is closed, projects rearwardly through a vertical slot 32 in the top wall of the port 20 and is there connected to the lower end of a sliding damper 33. 35 The sliding damper 33, which is illustrated more clearly in detail in Fig. 4, is formed by a flat sheet of metal having a slot 34 therein adapted to register with and open the port 27 at the top of the oven when 40 the damper is moved to its lowered position with its bottom end closing the port 20 below the oven. In moving to this lowered position the damper 33 through the arm 31 will move the valve 29 to open the safety 45 draft port 28 in the bottom wall 22 of the oven, thus permitting a sufficient draft to pass through the ports 28 and 27 to the stack to avoid smothering the burners. When the 50 sliding damper 33 is raised (see Fig. 4), its port 34 moves out of register with the oven port 27 so that the latter is closed while the bottom port 20 is opened. In order to enable this bottom port 20 to be fully 55 opened, the slot 32 is provided in its top wall so that the operating arm 31 for the damper 29 will pass thereinto. The sliding damper 33 is provided with suitable side guides 35 and it has a handle extension 36 which projects through the top 6 of the stove and is 60 provided with rack teeth 37 to set the damper in the desired adjustment. Air is admitted to the fire box below the burners by side and bottom dampers 38 and 39 and to prevent any of this air passing into the 65 flue 19 in an unheated condition, I provide in the lower portion of the fire box 12 a horizontal partition 40 extending from the bottom of the door 9 to the oven and forming a baffle wall closed except for two circular 70 ports 41 formed therein for the burners 11. Each of these ports is surrounded by a marginal upset flange 42, each flange being shaped and adapted to receive and hold the lower end of the burner chimneys 16 and to 75 center them in proper position relatively to

the burners. All entering air will therefore pass up through these ports 41 and supply the necessary oxygen for the burners and will pass in a highly heated condition 70 through the stove.

In operation, the hot gases, after flowing over and back under the oven, are shunted either through the port 20 into the bottom of the stack 21 or through the bottom ports 23 and 28 into the oven through which they 75 pass and enter the flue 21 through the port 27. As the sliding damper 33 is adjusted to open the port 27 and close the port 20, it moves with it the safety draft 29 and thus, regardless of the position of the valves 24, 80 will insure a sufficient draft to protect the burners against being smothered.

In Fig. 5 I illustrate a modified arrangement of the main damper corresponding to that shown in my Letters Patent. Here the 85 stack connects with a back flue 43 into which the ports 20 and 27 open. A winged damper 44 hinged to the back wall 5 is disposed in its raised position to close the port 27 and in its lowered position to close the flue 43 90 below the port 27 and thus serve in effect to close the port 20. An operating rod 45 is connected to the free end of the winged damper and to the operating arm 31 of the safety draft valve 29. By this arrangement 95 the ports 27 and 28 will be simultaneously opened or closed, motion being imparted by the ratchet arm 36 which, instead of being connected to the winged damper 44, is connected to a crank arm 46 by which the 100 damper is operated.

This invention is not intended to be restricted in scope to the specific embodiment shown, but contemplates such modifications as come within the spirit and scope of the 105 claims.

Having thus described my invention, what I claim as new and desire to secure by Letters Patent, is:—

1. An oil burning stove having therein an 110 oven about which the hot gases pass, a smoke flue, there being outlet ports for the hot gases opening from the oven and from below the oven into said flue, means to control the admission of hot gases into the oven, 115 damper means for said outlet ports, an auxiliary draft valve in the oven, and means to open said valve when the damper mechanism is set to pass the hot gases through the oven to said smoke flue.

2. The combination with an oil burning stove having therein an oven, a smoke flue and means to direct the hot gases about the oven, there being outlet ports for the hot gases opening into said flue below the oven 125 and near the top of the oven, means to admit hot gases into the bottom of the oven, a damper mechanism for simultaneously controlling said outlet ports and opening one as it closes the other, and a safety draft valve 130

in the oven bottom movable by said damper mechanism to open position when the damper mechanism is set to pass the hot gases through the oven to the smoke flue.

3. An oil burning stove comprising an oven, means to cause the hot gases to pass over and around under the oven, valve mechanism to admit the hot gases into the lower portion of the oven, a smoke flue, there being outlet ports for the hot gases entering said flue below the oven and near the top

of the oven, a common ported damper slideable in the smoke flue and adapted to open one of said outlet ports as it closes the other, and a safety draft valve in the bottom of the 15 oven connected to the sliding damper and adapted to be opened thereby when said oven outlet port is open.

In testimony whereof I affix my signature.
ARNOLD F. GLASS.
